ELECTRICAL MUSICAL INSTRUMENT

Galan W. Demuth, Westville, N. J., assignor to
 Radio Corporation of America, a corporation of
 Delaware

Application March 31, 1939, Serial No. 265,277

4 Claims. (CL 179—1)

This invention relates to electrical musical instruments and more particularly to the type of musical instruments wherein the vibrations of strings or other vibrating members are electrical-
 5 ly picked up either electromagnetically or electrostatically and transmitted preferably through an electronic amplifier to an appropriate sound reproducer. The invention is particularly applicable to pianos having electromagnetic pick-
 10 ups adjacent to the strings and wherein separate controls of the bass and treble volumes are required. In such devices it has heretofore been customary to group the treble pickups together in one circuit and to group the bass pickups to-
 15 gether in another circuit, each of these circuits having appropriate tone control or possibly even an individual amplifier.

In such an arrangement if the volume of output from the treble portion of the instrument, 20 for example, is made very low and the output from the bass portion is made very high, then as the player reaches the cross-over there is a sudden change in volume between two adjacent notes instead of a gradual change from the one 25 portion of the keyboard to the other. If, on the other hand, an amplifier is used having a characteristic which can be shifted one way or another so as to selectively accentuate the treble or the bass, a corresponding shift in tone quality 30 results. For example, if the bass is accentuated and the volume in the treble is decreased, then the corresponding overtones of the bass notes are decreased in amplitude.

In apparatus according to the present invention, 35 separate groups of pickups in the treble and in the bass are used each with its separate volume control to avoid distortion, but the notes at the adjacent ends of the treble and bass scales are provided with divided pickups, a portion of 40 the turns of the pickup coil being connected to the treble circuit and a portion of the turns being connected to the bass circuit. The number of turns in each pickup which are connected to the one output circuit may be progressively de-
 45 creased as the notes are farther away from that circuit, and the turns connected to the other circuit correspondingly increased. By the use of this arrangement, a sharp transmission point is avoided and a gradual progression from one portion 50 of the keyboard to another is accomplished independently of the relative volumes in the different portions of the keyboard and without any noticeable distortion.

It will be apparent that the application of the 55 invention is not limited to a transition between

the treble and bass portions of a piano keyboard but that the keyboard may be divided if desired into three or more parts, each with its appropriate volume control and with an appropriate group of transition pickups blending each of the sections into the next; as, for example, the groups may be divided into the treble, the intermediate, and the bass, or one group of pickups may be applied to the upper range of the piano where three string unisons are used for each note, another group of pickups to the middle and upper bass ranges where two string unisons are used, and a third group of pickups to the lower bass range where single strings are used with appropriate transition pickups at each 15 changeover point.

The invention, of course, is not limited to pianos or stringed instruments, but may be applied to different types of apparatus where a plurality of pickups or impulse sources are used to 20 cover an extended range of frequencies, as, for example, in electric organs and in instruments using tuning forks, vibrating bars or other equivalent generators of the sound frequencies.

Likewise the invention may be applied to elec- 25 trostatic, piezo electric or other types of pickup elements by using either sub-divided pickups as in the case of electromagnetic pickups or by using voltage or current dividers across the individual pickup units to direct appropriate portions of the 30 output to the higher and lower frequency output circuits.

One object of the invention is to provide an improved type of pickup system for electric mu- 35

Another object of the invention is to provide an electric musical instrument capable of producing different volume levels in different frequency ranges without distortion.

Another object of the invention is to provide 40 an apparatus having a smooth transition from one volume and frequency range to a different volume and frequency range.

Another object of the invention is to provide 45 an electric musical instrument having a plurality of independently controllable output circuits.

Another object of the invention is to provide 50 an electric musical instrument having a volume characteristic which can be varied according to frequency without producing distortion.

Other and incidental objects of my invention will be apparent to those skilled in the art from a reading of the following specification and an inspection of the accompanying drawing, in which

Figure 1 is a schematic diagram of my improved pickup circuit from the vibrating members to the amplifier input circuit, and

Figure 2 shows the response characteristic of 5 the circuit plotted against frequency.

Referring first to Fig. 1, the vibratable elements are indicated at 10 and in the form of the invention illustrated these may be vibratable strings, reeds, forks or the like, the higher frequency elements being toward the top of the sheet and the lower frequency elements being toward the bottom. The number of elements, of course, may correspond to any desired frequency range. For example, in a piano the number of notes would 10 ordinarily be 88, with a corresponding number of pickup locations and with a correspondingly greater number of strings. The high frequency pickups are generally indicated at 11 and 12, these pickups being in proper cooperative relation with 15 the high frequency vibrators. The low frequency pickups are indicated at 13 and 14. The high frequency pickups direct their output to the transformer 27 and the output control potentiometer 28, while the low frequency pickups direct 20 their output to the transformer 29 and the potentiometer 30. Between these two groups of pickups are provided the transition pickups schematically indicated at 15, 16, 17 and 18. These, 25 of course, may be considerably greater in number, being preferably spread over a range of the order 30 of an octave. The transition pickups 15 and 16 toward the treble end of the scale are provided with coils having a relatively large number of turns 19 and 20 which are connected to the treble 35 output transformer 27 and these pickups 15 and 16 are also provided with coils 21 and 22 having a smaller number of turns connected to the bass output transformer 29. The pickups 17 and 18 toward the bass end of the transition are provided 40 with coils 23 and 24 having the larger number of turns connected to the bass output transformer 29, while the coils 17 and 18 having the smaller number of turns are connected to the treble output transformer 27. It will be apparent 45 that the major portion of the output from the pickups 15 and 16 is delivered through the coils 19 and 20 to the treble output circuit, while the smaller portion of the output is directed through coils 21 and 22 to the bass output circuit 50 and its corresponding volume control. If therefore the treble volume control 28 is turned to a very low level, the output from these two pickups will be greatly reduced but a considerable portion thereof will be picked up by the coils 21 and 55 22 and may be reproduced at a fairly high level through the bass control 30. It will also be apparent that in the case of the pickups 17 and 18 a lowering of the volume from the potentiometer 28 will decrease the outputs from these pickups through the coils 17 and 18 but in a much less degree than with the pickups 15 and 16 and, therefore, as the notes sounded go progressively from the treble into the bass, the portion of the output of the vibrators will increase until the full 60 output is reached from the pickups 13 and 14.

The frequency characteristics of such a circuit over the range, for example, from 27 cycles to 4,000 cycles is indicated in Fig. 2 showing that at the lower end of the scale at 27 cycles, the bass circuit provides the entire output and at the higher frequency of 4000 cycles, the treble circuit provides the entire output. Over the transition range, however, when the output from the bass circuit is decreased a certain amount the 65 output of that same note through the treble cir-

cuit is increased by a corresponding amount, equal portions being directed through the bass and treble circuits at the middle of the transition.

As pointed out above, the number of turns fed into each circuit through the pickups over the 5 transition frequencies is varied in accordance with the number of notes over which the transition is spread and the ratio of turns in each pickup feeding to the respective circuits is preferably the corresponding fraction of the total number 10 of turns.

In the case of capacity pickups, the relative areas of the capacitors are preferably varied in the same proportion, and in the case of piezoelectric or similar pickups where size is not so 15 readily variable voltage dividers may be connected across each pickup in order to apportion the output correspondingly between the two output circuits.

It is well known to those skilled in the art that 20 over a portion of their range, pianos customarily have three strings for each note, over another portion of the range two strings for each note, and in the extreme bass, only one string for each note, and each of the groups of strings, although 25 producing only a single fundamental, produces many harmonics. In this case, I may associate one pickup with the strings of each note. Some types of electric organs, on the other hand, have a relatively small number of primary frequency 30 producing devices and in such cases, the main pickups are associated with only one, or possibly several, of the frequency producing devices for a single note, according to the harmonics desired, but the resultant frequencies may then be multiplied and selected for the individual notes to be produced, harmonics of the original notes to be selected may be reproduced, or several harmonics may be selected for reproduction. In the case of such an electric organ instead of applying my 40 selective pickups to the primary oscillation producers, I may apply them in the form of corresponding transformer windings to the secondary oscillation producers i. e. to the output of the circuits which determine the particular note to be 45 produced when any particular key is pressed, independently of which of the primary oscillators or sound producers the particular sound originates in. In the following claims, the reference to pickups corresponding with the number of note 50 producing means is to be construed in view of the foregoing explanation as indicating a correspondence to the keyboard and as referring to one or more strings in the case of instruments like the piano or with the fractional outputs from the 55 oscillators, tone wheels or the like, in the case of an electric organ.

Having now described my invention, I claim:

1. An apparatus of the class described including impulse sources of sequential frequencies, a plurality of output circuits each having a volume control therein, a plurality of pickups corresponding in number with said impulse sources, the pickups in one portion of the frequency range being connected to one of said output circuits, the pickups in another vicinal portion of the frequency range being connected to another of said output circuits and the pickups in the frequency range between the said two portions being connected to both of said output circuits. 60 65 70

2. An apparatus of the class described having a plurality of means for producing notes of sequential frequencies, a plurality of output circuits each having a volume control therein, a plurality of pickups corresponding in number with the note 75

producing means, the pickups in one portion of the frequency range being connected to one of said output circuits, the pickups in another vicinal portion of the frequency range being connected to another of said output circuits and the pickups in the frequency range between the said two portions being connected to both of said output circuits in proportion to their relative frequencies.

3. In apparatus of the class described having a plurality of means for producing notes of sequential frequencies, a plurality of output circuits each having a volume control therein, a plurality of inductive pickups corresponding in number with the note producing means, the pickups in one portion of the frequency range being connected to one of said output circuits, the pickups in another vicinal portion of the frequency range being connected to another of said output circuits, and the pickups in the frequency range be-

tween the said two portions each having a portion of its inductance connected to one and another portion of its inductance connected to the other of said output circuits.

4. The combination of a plurality of means for producing oscillations of different frequencies, a plurality of output circuits having volume controls therein, a plurality of pickups corresponding in number with the oscillation producing means, the said pickups in one portion of the frequency range being connected to one of said output circuits, the pickups in another portion of the frequency range being connected to the other of said output circuits and the pickups in the frequency range between the said two portions being connected to both of said output circuits.

GALAN W. DEMUTH.
